UNITED STATES PATENT OFFICE.

WALTER W. PHILLIPS, OF JERSEY CITY, NEW JERSEY.

STAIR-CARPET RETAINER.

1,355,775.

Specification of Letters Patent. Patented Oct. 12, 1920.

Application filed February 20, 1920. Serial No. 360,039.

To all whom it may concern:

Be it known that I, WALTER W. PHILLIPS, a citizen of the United States, and a resident of Jersey City, in the county of Hudson and State of New Jersey, have invented a new and Improved Stair-Carpet Retainer, of which the following is a full, clear, and exact description.

This invention relates to carpet retainers especially adapted for use on stair steps and has particular reference to devices of the general nature set forth in Letters Patent of the United States No. 1,091,862, issued to me on the 31st day of March, 1914.

Among the objects of the present invention is to provide a retainer for stair carpets that will be held in place with more reliability and so will hold the carpet more securely in proper alinement than in my previously patented device, by reason of certain auxiliary metallic attachments for the main holding devices.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a perspective view of a section of stairs indicating one form of my improvement in use thereon.

Fig. 2 is a vertical sectional view of the same on the line 2—2.

Fig. 3 is a perspective view of a section of stairs with a modification of my improvement in use thereon.

Fig. 4 is a sectional detail on the line 4—4 of Fig. 3.

Fig. 5 is a fragmentary front elevation of a further modification.

Fig. 6 is a detail perspective view of a form of attachment clip shown in Fig. 5.

Referring now more specifically to the first two figures I show my improvement as including a pair of metallic holders in the form of plugs 10 adapted to be secured rigidly in the riser 11 and just below the next upper tread 12. These plugs 10 have horizontal holes 10' extending inward from the face of the riser into which the right angularly bent ends 13 of the vertical leg

portions 14 of the carpet retainer 15 are adapted to be projected when the retainer is compressed and put under sufficient force for the purpose for which it is intended. 60 The horizontal bar extending between the leg portions 14 coöperates with the run of the carpet to hold it in the corner between the riser and the tread of the next lower step as set forth in my previous patent. It 65 will be understood that the retainer as a whole has sufficient strength and flexibility not only to adapt itself to its function but also to be self-retaining. As will be understood from Fig. 2 the retaining bar 15 can 70 not ordinarily be pulled forward along the next lower tread because of the rigidity of the legs 14. Any tension on the bar 15 tending to draw it forward will set up additional friction between the ends 13 and the plugs 75 10, and so the legs cannot be drawn bodily forward. Consequently the retainer will be held firmly in place by reason of the plugs. When it is desired, however, to detach the retainers the operator will apply a screw 80 driver or other similar tool to the upper ends of the legs for the purpose of releasing the ends 13 from the holes 10' of the plugs. When thus set free from the plugs the retainer will of course be free to be removed 85 from the carpet.

In Figs. 3 and 4 I show a retainer comprising a bar 15 and upright legs 14, the same terminating in points 16 which engage beneath the overhanging portion of the next upper tread as in my previous patent, but I have found that it is desirable to provide auxiliary means to prevent the tendency for the carpet to draw forward upon the bar 15, a condition which naturally would result in 90 the loosening of the points of contact with the next higher tread. To accomplish this in another way from that shown in Figs. 1 and 2 I provide a pawl 17 pivoted upon the end portions of the bar 15 adjacent to the bends leading into the legs 14, and hence just at the edges of the carpet. These pawls are adapted to rotate freely on the bar 15 and have downwardly projecting points which engage automatically with the upper 100 surface of the adjacent tread and so prevent the forward movement of the bar 15. Any tendency of the carpet to draw forward will be resisted immediately by the bar, and the bar will be held from such forward movement by the pawls. These pawls cannot turn relatively around the bar 15 so long as 105 110

their points engage into the step unless the bar 15 will move upward and swing outward in an arc of a circle around the points of the pawls. This movement, however, of the bar is resisted by the downward pressure due to the rigidity of the leg portions 14 of the retainer.

In Figs. 5 and 6 I show an auxiliary clip or holder for the carpet retainer comprising 10 a pair of socket pieces 18 made as rights and lefts and preferably in the form of angle members, the outer vertical edge portion of which is provided with a swaged form at 19, the swaging extending around the corner 15 and adapted to receive the upper end 13' of each leg which is shown as being bent toward the opposite leg and in a plane parallel to the vertical plane of the riser to which the socket members 18 are adapted to be secured 20 rigidly as by means of screws 20. The sockets into which the ends 13' are fitted may be open at the sides so that the ends of the legs may be snapped into the same from the opposite sides of the socket members, 25 but when so inserted the legs and bar 15 connecting them will be held rigidly from forward movement along the next lower tread. Obviously, however, to remove these re-

tainers to release the carpet the operator simply has to draw the upper ends of the 30 legs laterally from beneath the socket members against the rigidity of the legs and so the retainers will be released.

I claim:

1. In a stair carpet retainer, the combination with a bar adapted to engage over the carpet and leg portions at the ends of the bar adapted to extend between the carpet and the surface of the next upper riser, of auxiliary metallic means coöperating with 40 the leg portions of the retainer and said riser to hold the retainer in retaining position.
2. A stair carpet retainer of the nature set forth in claim 1 in which said auxiliary 45 holding means coöperates with the stair structure and the ends of the leg portions remote from the bar.
3. A stair carpet retainer of the nature set forth in claim 1 in which the ends of the 50 leg portions are bent at an angle and the auxiliary holding means consist of metal plates embracing said bent ends holding them against the riser.

WALTER W. PHILLIPS.
